AUTOMATIC CIRCUIT BREAKER

Filed Aug. 2, 1937

Fig. 1.

A cross-sectional view of a cylindrical component, likely a piston or cylinder. The component is divided into several sections by horizontal lines. The top section is labeled '31' and contains a small cavity. Below this is a section labeled '30' with a central vertical channel. The next section is labeled '29'. The main body of the cylinder is labeled '24' and has a hatched pattern. A central vertical rod passes through the cylinder, with sections labeled '14', '32', '33', '37', '39', '35', and '36' from top to bottom. The bottom section of the cylinder is labeled '13'. At the very bottom, there is a base labeled '15' with a flange labeled '16' and a central hole labeled '17'. The number '18' is also present near the base. The entire diagram is labeled 'FIG.' in the top right corner.

UNITED STATES PATENT OFFICE

2,155,758

AUTOMATIC CIRCUIT BREAKER

Marion Kelly Hinde, Atlanta, Ga.

Application August 2, 1937, Serial No. 157,058

3 Claims. (Cl. 180—82)

This invention relates to improvements in circuit breakers in general, and has particular reference to a circuit breaker adapted to be mounted on an automobile for the purpose of automatically breaking the electric circuit of the automobile whenever the automobile becomes either inverted or tilted at a dangerous angle.

In the prior art circuit breakers have been applied to automobiles for this purpose, but the break in the circuit upon inversion or tilt of the automobile occurs only while the vehicle is inverted or tilted and becomes closed when the vehicle is returned to proper position. This frequently results in setting fire to the vehicle, because the inversion, whether due to collision or otherwise, usually effects the release of gasoline fumes or vapors which are likely to cause fire by coming in contact with live wires.

It is the main object of the present invention, therefore, to provide a circuit breaker in the electric circuit of a motor vehicle, which will break the circuit upon inversion of the vehicle or its tilt to a dangerous angle, and which will maintain the circuit broken after the righting of the vehicle and until the circuit is deliberately closed by an operator.

This application is a continuation in part of my Patent 2,099,483, November 16, 1937.

In the drawing:

Figure 1 is an elevation of a preferred form of the invention, part of the enclosing casing being broken away to show details of construction;

Figure 2 is a vertical section taken on the line 2—2 of Figure 1;

Figure 3 is a vertical section taken on the line 3—3 of Figure 1; and

Figure 4 is a vertical section taken lengthwise through a modification of that part of the apparatus illustrated in Figure 3.

Referring to the drawing, in which similar parts are designated by like numerals:

The elements comprising the circuit breaker are enclosed in the casing of insulating material. To facilitate disclosure, however, only two of the walls of this casing are shown in the drawing. The rear wall 5 is suitably secured at right angles to a side wall 6, by means of the angle brackets 7 and 8.

A cylindrical container 9 for a conducting liquid, such as mercury, is suitably secured to the back wall 5 by means of a strap 10, having its opposite ends bent to form outwardly directed flanges 11, which are secured to the wall 5 by means of bolts 12. Only one of these flanges 11 and bolts appear in the drawing. However, the

invention is not concerned with any particular means for securing the container to the wall 5.

The container 9 comprises the lower part 13 of conducting material screw-threaded at its upper end, to an insulating part 14. The bottom 15 of the container is provided with an aperture 16, to receive a conducting bolt 17, locked to the bottom 15 by means of the lock nut 18 and washer 19. A second nut 20, screw-threaded on to the bolt 17, is used to clamp a contact terminal 21 against washer 19 to connect it to the lower part 13 of the container 9. The upper part 14 is made of insulating material and has the head 22 thereof apertured axially to receive the conducting member 23, which is provided with a head 24, seated in a counter-sink 25, formed in said head 22.

The lower part of the member 23 is screw-threaded to receive a nut 26 which serves to clamp the conducting disk 27 against a shoulder formed on the member 23. The disk 27 is of the same diameter as the interior of the cylindrical member 9 and serves as a contact element between the conducting part 13 of the cylinder and the conducting member 23, when the cylinder is moved from a vertical to a horizontal position, and the mercury 28 contained in the cylinder closes the circuit between the conducting part 13 and the member 23 through the disk 27. The upper end of the member 23 is axially bored and screw-threaded to receive a conducting screw 29, used to clamp the contact terminal 30 against a washer 31, which is in conducting contact with the said member 23.

To prevent grounding of the circuit by splashing of the mercury in the container 9, due to the passage of the vehicle over rough roads, and without any tilting of the cylinder into horizontal position, the lower end of the member 23 is provided with an externally screw-threaded projection 32 to which is detachably connected a rod 33 of insulating material. Spaced apart along the rod 33 is a series of disks 34, 35 and 36, suitably secured in position by means of screws 37. The disks 34, 35 and 36 are beveled downwardly 45 so as to deflect downwardly in the cylinder 9, any mercury which might come in contact with the beveled periphery of these disks by vertical splashing of the mercury. Preferably the disks increase in diameter with their distances from the bottom of the cylinder, so as to effectively prevent short-circuiting of the system by splashing of the mercury due to the passage of the vehicle over rough roads.

Contact terminal 21 is connected by a wire 38 to

to a conducting plate 39, suitably secured to the back wall 5 of the casing. A second wire 40 extends from the same plate to the ammeter of the system. A clamping nut 42 secures the terminals of the wires 38 and 40 in electrical contact with the plate 39.

The plate 39 has suitably pivoted thereto, an armature 43 of conducting material and adapted to rest normally by gravity against a stop 44 suitably secured to and projecting from the rear wall 5 of the casing. The armature 43 terminates at its free end in a hook 45, adapted to engage the upper free end of a conducting strap 46, pivoted at its lower end to swing about the shank 47 of a pivot bolt suitably secured as by nuts 48 and 50, to and projecting from the rear wall 5 of the casing. A contact terminal 48, clamped between the two nuts 49 and 50, is connected by a wire 51 to a source of electric supply.

20 A strong wire spring 52 is wrapped around the nuts 49 and 50, which secure the pivot bolt 47 to the rear wall 5. One branch of the spring 52 extends along the inner face of the rear wall 5 into contact with a stop 53 suitably secured to said wall 5. The other branch of the spring 52 extends upwardly in the casing and is bent at its upper end to form a transverse member 54, which contacts with the inner face of the strap 46 and forces the upper end of that strap into electrical contact with the hook 45 on the end of the armature 43.

25 The apparatus includes an electrical magnet 55, suitably secured as by angle bracket 56 to the rear wall 5 of the casing. One terminal of the magnet 55 is connected by a wire 57 to the contact terminal 30 at the upper end of the liquid container 9. The other terminal of the electrical magnet is connected by a wire 58 to ground.

30 It will be apparent from Figure 1 of the drawing, that when the magnet 55 becomes energized, the armature 43 will be drawn from its stop 44 to release the strap 46; and the spring 52 will cause this strap 46 to move against the projecting end 59 of a re-setting plunger 60, which is slidably mounted in an externally screw-threaded collar 61, having a flange 62 at its outer end clamped against the outer face of wall 6 by means of the nut 63. The end 61 is screw-threaded to receive the nut 64, which acts as a stop to limit the outward movement of the plunger 60 in the collar 61. A compression spring 65 is interposed between the flange 62 and a handle 66 on the plunger to maintain the plunger normally retracted.

35 The circuit closer shown in Figure 4, comprises a cylindrical container 67, made of glass or other insulating material. The upper part of the container is closed by a cover 68 of conducting material, centrally apertured and counter-sunk to receive the conducting member 69. A rod 38' of insulating material is secured to the inner end of the member 69, and is provided with the anti-splash members 34', 35' and 36', secured to the rod by the screws 37.

40 In this form of container, the wire 38 is clamped to an annular band 70 of conducting material seated in an annular recess 71 and having a screw-threaded conducting rod 72 projecting through the wall of the container 67 to form with the washer 73 and nut 74, a clamping terminal for the wire 38.

45 The device, when in operative position, is suitably secured to any part of an automobile, with the container 9 or 67, as the case may be, in vertical position. Referring now to the form of the invention shown in Figure 1, it will be apparent

5 that when the conducting strap 46 is in locked engagement with the armature 43, the circuit controlling the operation of the automobile is completed through wire 51, strap 46, armature 43, and wire 40. In the event of such overturn 10 of the automobile that the container 9 becomes horizontal, it will be evident that the mercury 28 in the container will close the circuit through the conducting part 13, disk 27, the wire 57, electromagnet 55, wire 58, to ground, the other terminal 10 of the container being connected by wire 38 to the armature 43.

15 Upon closing of the circuit through the magnet 55, the armature 43 becomes attracted toward the core of the magnet, and immediately releases the conducting strap 46 to break the circuit, as well as the circuit through the magnet. These circuits remain broken until the automobile is restored to upright position, and until the strap 46 is forced back into operative engagement with the armature 43, by operation of the plunger 60. In the manufacture of this device, it is particularly essential that the hook part 45 of the armature shall be inclined sufficiently to prevent disengagement of the armature from the strap 46 by any movements of the vehicle other than that which causes energization of the magnet 55. The upper end of the strap 46 must be correspondingly shaped to ensure good locking and electrical contact with the hook 45.

20 Numerous variations may doubtless be devised by persons skilled in the art without departing from the principles of my invention. I, therefore, desire no limitations to be imposed on my invention, except such as are indicated in the 30 appended claims.

What I claim is:

1. A vehicle having a main electric circuit system including a source of current, a circuit maker and breaker for said system comprising a support, an electro-magnet, an armature for said magnet pivoted at one end to said support and having a hook at its free end, a stop for supporting said armature normally in substantially horizontal position, means for connecting the pivoted end of said armature to said source, a conducting strap connected at one end to said source and having its other end normally in locked engagement with said hook to close the main circuit of said system through said armature and means, yielding means for moving said strap out of the path of said hook when the armature is removed from strap locking position by energization of said magnet, and means connected at one end to the pivoted end of said armature and grounded at its other end through said electro-magnet and operable only by overturn of the vehicle to substantially horizontal position to energize said magnet and move the armature from locking engagement with said strap, whereby the circuit system is broken and the magnet deenergized.

2. A vehicle having a main electric circuit system including a source of current, a circuit maker and breaker for said system comprising a support, an electro-magnet, an armature for said magnet pivoted at one end to said support and having a hook at its free end, a stop for supporting said armature normally in substantially horizontal position, means for connecting the pivoted end of said armature to said source, a conducting strap connected at one end to said source and having its other end normally in locked engagement with said hook to close the circuit of said system through said armature and means, yielding means for moving said strap out of the path

of said hook when the armature is removed from strap locking position by energization of said magnet, means connected at one end to the pivoted end of said armature and grounded at its other end through said electro-magnet and operable only by overturn of the vehicle to substantially horizontal position to energize said magnet and move the armature from locking engagement with said strap, whereby the circuit system is broken and the magnet deenergized, and means for moving said strap into locking engagement with said armature upon restoration of the vehicle to normal operative position.

3. A vehicle having a main electric circuit system including a source of current, a circuit maker and breaker for said system comprising a support, an electro-magnet, an armature for said magnet pivoted at one end to said support and having a hook at its free end, a stop for supporting said armature normally in substantially horizontal position, means for connecting the pivoted end

of said armature to said source, a conducting strap connected at one end to said source and having its other end normally in locked engagement with said hook to close the circuit of said system through said armature and means, yielding means for moving said strap out of the path of said hook when the armature is removed from strap locking position by energization of said magnet, means connected at one end to the pivoted end of said armature and grounded at its other end through said electro-magnet and operable only by overturn of the vehicle to substantially horizontal position to energize said magnet and move the armature from locking engagement with said strap, whereby the circuit system is broken and the magnet deenergized, and a plunger slidably mounted on said support to move said strap into position for locking engagement with said armature.
